UNITED STATES PATENT OFFICE.

RAY TITUS MOODY, OF KEENE, NEW YORK.

REVERSING MECHANISM FOR INTERNAL-COMBUSTION ENGINES.

1,318,684.

Specification of Letters Patent. Patented Oct. 14, 1919.

Application filed December 21, 1918. Serial No. 267,822.

To all whom it may concern:

Be it known that I, RAY T. MOODY, a citizen of the United States, residing at Keene, in the county of Essex and State of New York, have invented certain new and useful Improvements in Reversing Mechanism for Internal-Combustion Engines, of which the following is a specification, reference being had to the accompanying drawings.

10 This invention relates to internal combustion engines, and particularly to means for reversing an internal combustion engine.

The general object of this invention is to provide a mechanism of this character in 15 which a reversal of the engine is secured by reversing the cam which operates the exhaust valve, this reversing device being particularly useful in portable sawing outfits where it is often necessary to use a left hand 20 sawing machine in case no provision for reversal is made or run with a cross belt which causes loss through friction and a great deal of extra wear on the belt.

A further object is to provide a mechanism 25 of this character including a reducing gear wheel, which is operatively connected to the crank shaft, and a cam mounted upon and rotatable by the reducing gear wheel, and mechanism whereby the cam may be 30 shifted with relation to the reducing gear wheel so as to thereby change the instant at which the exhaust valve opens, and in this connection provide a mechanism of this character wherein the cam is releasably 35 latched to the reducing gear wheel so that when unlatched it may be shifted to a reverse position by engagement with the operating stem of the exhaust valve.

Other objects will appear in the course of 40 the following description.

My invention is illustrated in the accompanying drawings, wherein:—

Figure 1 is an elevation of my improved reversing mechanism for internal combustion engines.

Fig. 2 is a sectional view of the device; and

Fig. 3 is a detail face view of a reducing gear employed in the mechanism.

50 Referring to these drawings, 10 designates a portion of the engine base of an internal combustion engine having brackets 11, providing bearings for an operating rod or shifter rod as will be later described. The 55 inner face of the member 10 is cut away as

at 12, and this member 10 is formed with a transversely extending bore or bearing 13. Mounted in this bore is a shaft 14, which is tubular, and mounted upon the shaft 14 to rotate therewith, is a reducing gear 15 of 60 the usual type adapted to be geared to the crank shaft of the engine in the usual manner.

Carried upon that portion of the tubular shaft 14 which extends beyond the reducing gear 15 is a cam 16, which is loose upon the shaft and adapted to turn freely thereon when not locked to the reducing gear. Longitudinally shiftable through the tubular shaft 14 is a latch rod 17, the extremity of 70 which carries an angularly bent portion 18 which at its extremity is inwardly turned as at 19, and adapted to enter a perforation 20 in the cam. The reducing gear 15 is formed at two points with perforations 21 into 75 which the terminal end 19 of the latch rod passes. When this latching rod is shifted outward so as to carry its terminal end slightly beyond the face of the reducing gear 15, then it will be obvious that the cam will 80 be free to rotate independently of the reducing gear while when the latching rod is drawn inward and its terminal end 19 enters one of the perforations 21, the cam will be 85 locked to the reducing gear.

The latching rod 17 is shifted into or out of its locking position by means of an operating rock shaft 22, one end of which is angularly bent as at 23 and forked at its extremity, this forked end engaging an annular groove 24 in the inner end of the rod 17. The opposite end of the rock shaft 22 is provided with a lever or arm 25 whereby the shaft may be rocked. This lever arm may be connected by suitable levers or connections to any desired operating member or it may constitute the operating member itself.

In order to prevent the cam from turning too far or in other words to limit the movement of the cam relative to the reducing gear 15 so that the cam shall simply shift to its reverse position and not beyond this point, I form on the outer face of the reducing gear 15 the arcuate groove 26, and the inner face of the cam 16 is formed with the 100 inwardly projecting stud 27, which engages in this groove 26. This groove is of sufficient length to permit the cam to have a rotation of approximately one-third of a complete circle upon the reducing gear. 110

Preferably a spring 28 will be provided which may engage the rock shaft 22 of the rod 17 and which will urge the latch rod 17 toward the cam so as to cause the terminal 5 end 19 to snap into position in one or the other of the perforations 21 when the operating lever 25 is released. With this construction when the cam is in one position the engine will operate as usual and will run in 10 one direction, but in order to reverse the engine the rock shaft 22 is operated in a direction to shift out the latch rod 18 and then when the cam strikes the roller 30 on the end of the exhaust valve stem 29, the roller will 15 force the cam back to its offset position and as soon as this position has been reached, the latch will snap into the corresponding perforation 21, locking the cam there and the engine kicks back and reverses.

20 In reversing the engine, the engine can be slowed down until it almost stops. Then the lever 25 is lifted up and as soon as the long end of the cam strikes the roller on the push rod the lever is allowed to snap back 25 into place and it will latch in its opposite position with the cam reversed from what it was before. By providing means for reversing the engine, the engine may run in opposite directions, thus changing the wear on the 30 bearings and economizing in wear and tear on the engine and further because different pieces of material run in opposite directions, and where an engine is to be shifted from use with one piece of machinery to use with 35 another and the engine is not reversible, cross belts have to be used which means a loss of power through friction. It will, of course, be understood that the reducing gear may be connected to the crank shaft of the engine 40 by any suitable intermediate gears but should run at a speed one-half that of the engine, as is usual.

It will be seen that this device is very simple, that it may be readily applied to all 45 types of internal combustion engines in which the exhaust valve is operated by a cam shaft, or equivalent element, and that it permits the very easy reversal of the engine. While I have illustrated a form of my 50 device which I have found to be particularly effective in actual practice, yet I do not wish to be limited to this, as it is obvious that many changes may be made in the details of construction and arrangement of parts 55 without departing from the spirit of the invention as defined in the appended claims.

I claim:—

1. In an internal combustion engine, an 60 exhaust valve stem, a gear wheel operatively driven from the crank shaft of the engine, a cam rotatively mounted upon the shaft of the gear wheel and coacting with the exhaust valve stem, means manually 65 shiftable independently of the cam or gear

wheel or unlocking it therefrom to permit it to shift when in contact with the exhaust valve stem, and means for limiting the rotation of the cam relative to the gear wheel.

2. In an internal combustion engine, an exhaust valve stem, a gear wheel operatively driven from the crank shaft of the engine, a cam rotatively mounted upon the shaft of the gear wheel and coacting with the exhaust valve stem, a member, manually shiftable independently of the cam or gear wheel for locking the cam to the gear wheel or unlocking it therefrom to permit it to shift when in contact with the exhaust valve 75 stem, the confronting faces of the gear wheel and the cam being formed one with a groove and the other with a pin engaging with the groove, the pin and groove limiting the rotation of the cam relative to the gear wheel. 80

3. In an internal combustion engine, an exhaust valve stem, a gear wheel operatively connected to the crank shaft of the engine and driven thereby, a tubular shaft upon which the gear wheel is mounted, a longitudinally shiftable and rotatable shaft passing through the tubular shaft, a cam loosely mounted upon the first named shaft and against the face of the gear wheel, said cam coacting with the exhaust valve stem, a radially projecting arm carried by the second named shaft and having an angularly bent terminal portion, the cam having a perforation through which the terminal portion passes and the gear wheel having a pair of 90 perforations spaced from each other and into which the terminal end of the arm is adapted to engage, the confronting faces of the cam and gear wheel being provided, one with an arcuate groove and the other with a stud engaging in the arcuate groove to limit the independent rotation of the cam, and manually controlled means for shifting the central shaft longitudinally to shift the terminal end of the arm out of engagement 95 with the gear wheel to thereby permit the exhaust valve stem, bearing against the cam, to shift it relative to the gear wheel to thereby reverse the operation of the engine. 100

4. In an internal combustion engine, an 115 exhaust valve stem, a gear wheel operatively connected to the crank shaft of the engine and driven thereby, a tubular shaft upon which the gear wheel is mounted, a longitudinally shiftable and rotatable shaft passing through the tubular shaft, a cam loosely mounted upon the first named shaft and against the face of the gear wheel, said cam coacting with the exhaust valve stem, a radially projecting arm carried by the second 120 named shaft and having an angularly bent terminal portion, the cam having a perforation through which the terminal portion passes and the gear wheel having a pair of 125 perforations spaced from each other and 130

into which the terminal end of the arm is adapted to engage, the confronting faces of the cam and gear wheel being provided, one with an arcuate groove and the other with a 5 stud engaging in the arcuate groove to limit the independent rotation of the cam, and a manually operable rock shaft having a bifurcated arm thereon operatively engaging the

central shaft to shift it longitudinally when the rock shaft is rocked.

In testimony whereof I hereunto affix my signature in the presence of two witnesses.

RAY TITUS MOODY.
